UNITED STATES PATENT OFFICE.

IRA G. NICHOLS, OF MANDAN, NORTH DAKOTA.

DENTURE.

Application filed June 24, 1921, Serial No. 480,119. Renewed May 15, 1923.

To all whom it may concern:

Be it known that I, IRA G. NICHOLS, a citizen of the United States, residing at Mandan, in the county of Morton and State of 5 North Dakota, have invented new and useful Improvements in Dentures, of which the following is a specification.

This invention relates to improvements in removable dentures, the general object of 10 the invention being to provide means for movably connecting the denture to a tooth so that the denture can have limited movement in relation to the tooth so as to relieve the tooth from undue strain caused by 15 the tendency of the denture to move under mastication of food.

This object is secured by providing a cylinder and piston arrangement for connecting the denture to the tooth, the cylinder 20 being closed to prevent food from entering the same.

This invention also consists in certain other features of construction and in the combination and arrangement of the several 25 parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a perspective view showing 35 one way of carrying out the invention.

Figure 2 is a similar view with the parts detached.

Figure 3 is an enlarged sectional view of the cylinder and piston device.

Figure 4 is a view of a modified form of piston.

In these views 1 indicates a two-part denture, the two plates A and B of which carry the restoration or false-teeth C and 45 are connected together by the bar 2. Adjacent each end of this bar a projection 3 is located which will hereinafter be referred to as a piston. A bar 4 is provided which carries the clasps 5 for engagement with the natural teeth (not shown) of the patient; these teeth serving as abutment teeth from 50 which the plates are supported. This bar also carries the cylinders 6 which are adapted to receive the pistons 3.

When the bar 4 is connected with the abutment teeth, the inner open ends of the

cylinders 6 are presented toward the alveolar border or borders and receive the pistons 3 of plate A and B; these plates fitting over and adhering to the gums of the 60 mouth by suction in the usual manner well known in the art. It will thus be seen that while bar 4 remains stationary with the abutment teeth to which attached, the piston attachments allow for the restoration, that 65 is, plates A and B, to move toward the alveolar borders without bringing any undue stress upon the abutment teeth from which the cylinders are supported. This will relieve the teeth to which the clasps are connected of strain while masticating food and at the same time hold the bridgework in place.

The outer end of each cylinder is closed 70 to prevent food from entering the same and a collar 7 is formed on each piston which acts as a stop against the open end of the cylinder to prevent the bottom of the piston from striking the bottom of the cylinder, a small space being left between the bottom 75 of the piston and the bottom of the cylinder when the collar is in engagement with the end of the cylinder. The piston may be made either of cylindrical shape or of tapered shape, the tapered piston being shown 80 in Figure 4. When the cylindrical piston is used a groove 7' is formed therein to prevent the formation of a vacuum in the cylinder 85 which would be apt to prevent movement of the parts.

In practice, the attachment is applied in the following manner. The bar 2 is arranged crosswise of a dental mold upon which the restoration plates A and B are to be formed, and bar 4 is arranged over 90 bar 2 with the cylinders engaging over pistons 3, as shown in Figure 1. The clasps 5 are then suitably anchored to the mold to hold the attachment in place and plates A and B are then formed or built up on each 95 side of the mold and moulded onto the ends of bar 2, as seen in Figure 3. As thus completed the device consists of the clasp bar 4 and the removable denture or bridgework, which, in the present instance, includes the 100 bar 2 which carries the restoration A and B or lost part which has been replaced. The advantage of the piston and cylinder attachments with this double bar for the connection of removable dentures or bridgework is 105 that resiliency is taken care of in masticating force towards the tissue without allowing 110

the removable denture or bridgework to move bucco-lingually or occlusally. Consequently, it prevents a strain or undue strain on the abutment teeth which is disastrous and later means the loss of the teeth.

I desire it to be understood that I may make changes in the construction and in the combination and arrangement of the several parts, provided that such changes fall within 10 the scope of the appended claims.

What I claim is:—

1. A removable denture attachment comprising a resilient bar having clasps associated therewith for engaging abutment 15 teeth and presenting vertical cylinders, a denture or restoration part, and a spring bar carrying said part and having vertical pistons engageable in the said vertical cylinders of the other bar.
- 20 2. A removable denture attachment comprising a curved resilient bar having clasps at each end for engagement with abutment teeth a vertical cylinder extending from

each end of the said bar adjacent a clasp thereof a two-part denture, and a spring bar 25 connecting the parts of the said denture and curved in conformity with the first mentioned bar, said last mentioned bar having vertical pistons slidably engaged in the said vertical cylinders.

3. A removable denture attachment comprising an upper and a lower resilient bar, clasps carried by one bar for securing the same to abutment teeth, a vertical cylinder carried by each clasp, vertical pistons carried by the other bar and working in the said cylinders, said pistons being shouldered at the bottom to provide stops for abutment with the said cylinders and limiting the movement of the pistons therein to provide 40 an air space at the inner end of the piston, said piston-carrying bar serving as a carrier or support for a restoration.

In testimony whereof I affix my signature.

IRA G. NICHOLS.
